UNITED STATES PATENT OFFICE

145,785

DESIGN FOR A LABORATORY WORKBENCH

Johan Bjorksten, Chicago, Ill.

Application September 4, 1945, Serial No. 121,835

Term of patent 14 years

(CL. D80—11)

To all whom it may concern:

Be it known that I, Johan Bjorksten, a citizen of the United States, residing at 5534 S. Cornell Avenue, Chicago, in the county of Cook and State of Illinois, have invented a new, original, and ornamental Design for Laboratory Workbench, of which the following is a specification, reference being had to the accompanying drawings, forming part thereof.

Figure 1 is an end elevational view of a laboratory workbench showing my new design;

Figure 2 is a side elevational view;

Figure 3 is a top plan view thereof; and
Figure 4 is a top perspective view.

In Figure 1 the end opposite to the one seen is identical with the end shown in the figure, as the design is symmetrical. The characteristic features of my design reside in the portion shown by means of full lines in the drawings.

I claim:

The ornamental design for a laboratory workbench, substantially as shown and described.

JOHAN BJORKSTEN.
